UNITED STATES PATENT OFFICE.

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY.

HIDE-STRETCHING APPARATUS.

Application filed September 20, 1920. Serial No. 411,370.

To all whom it may concern:

Be it known that I, GEORGE GODDU, a citizen of the United States, residing at Winchester, in the county of Middlesex and 5 State of Massachusetts, have invented certain Improvements in Hide-Stretching Apparatus, of which the following description, in connection with the accompanying drawings, is a specification, like reference characters on the drawings indicating like parts in the several figures.

This invention relates to hide stretching apparatus.

After tanning, hides are commonly 15 stretched by pincers and nailed to wooden frames on which they are left to dry. The frames are rectangular and difficulty is experienced in stretching the hides taut at every part, especially when the hides are 20 irregular in shape. Also the nails frequently drop on the floor when the hide becomes dry and thus are wasted or else they stick in the hides and interfere with subsequent operations.

25 It is an object of the invention to provide an improved hide stretching apparatus which will avoid the difficulties enumerated. In the preferred embodiment of the invention, a series of hide engaging members are 30 mounted permanently on a frame and each member is formed with diverging prongs which can grip the hide to tension it in two directions. The prongs are arranged preferably in a plurality of transverse and longitudinal series extending over the greater 35 part of the frame so that some of the prongs are always in a position to grip the hide even though it be irregular in shape or vary in size.

40 Referring to the drawings,—

Fig. 1 is a perspective view of the hide stretching apparatus showing somewhat diagrammatically the arrangement of the hide gripping prongs;

45 Fig. 2 is a section on the line 2—2 of Fig. 1;

Fig. 3 is a perspective view showing a portion of the frame and the manner in 50 which the hide engaging prongs are mounted;

Fig. 4 is a plan view of a portion of the frame;

55 Fig. 5 is a perspective view showing the manner in which the frames are hung while the hides are drying;

Fig. 6 is a detailed perspective view of one of the hide engaging members.

At 8 is indicated generally the frame which is composed of outer and inner longitudinal bars 10 and 12, respectively, which 60 are attached to outer and inner transverse bars 14 and 16. Suitable diagonal braces 18 may be interposed between the bars 12 and the corners of the frame as indicated and, at two of the corners, suitable angular 65 projections 20 may be attached which serve to support the frame slidably on the elevated slidways 21, as indicated in Fig. 5.

To support the hide and the hide engaging prongs upon the framework, series of 70 angle irons are provided. These consist of both longitudinal and transverse members, the longitudinal members comprising projecting supporting flanges 22 and horizontal flanges 23 secured to the frame. These members extend longitudinally of the frame 75 from one diagonal brace 18 to the other and lie parallel to and between the bars 10 and 12 of the frame. The transverse members comprise projecting supporting flanges 24 and horizontal flanges 25. These members extend transversely from one diagonal brace 18 to the other and they also connect the inner longitudinal bars 12 of the frame. At the center of the frame, the angle irons may 80 be dispensed with as indicated at 26 in Fig. 1, this area being slightly less than the area 85 of the smallest hide to be stretched.

To secure the hide engaging prongs to 90 these angle irons the latter are provided with series of lower openings 27 and series of upper openings 28, these openings being arranged in staggered relation so that the upper openings in one angle iron will come 95 opposite the lower openings in the adjacent angle iron. Suitable cutaway portions 29 to accommodate a tool are provided on each flange 22 and 24, these portions being arranged above the lower openings 27 and opposite the upper openings 28 of the adjacent angle iron.

As indicated more particularly in Figs. 3 and 6, the hide engaging members consist of a shank portion 30 which is inserted through the openings 28 and 27, one end of the shank being slit as indicated at 32 so that the ends may be spread apart to secure the shank in position against endwise movement. Near the other end of the shank there are shoulders 34 which engage the flanges 22 adjacent 105 110

the openings to resist rearward movement of the hide engaging members and this end of the shank is cut as indicated at 36, 38 to provide a pair of prongs or points 40 extending forwardly and laterally. Each of these prongs is bounded by three surfaces, two of which are indicated at 42, 44, and thus a substantially triangular end is produced on which the points 40 are formed.

10 In Figs. 2 and 5 half of a hide is indicated at H. In attaching the hide, the operator first secures one edge of the hide to some of the prongs 40 and then with a pair of pincers he works around the hide, pulling the edge of the hide down over the prongs 40. The cutaway portions 29 coming opposite the prongs allow him to have access to the edge of the hide all the way around the frame and the prongs 40, since they diverge somewhat, provide means whereby an irregularly shaped hide may be easily fastened since any of the points 40, as may be most convenient, can be stuck into the hide. The feature is of special importance near the diagonals of the frame since that is the part of the frame which is usually covered by the more irregular portions of the hide.

Although the invention has been described as embodied in apparatus especially designed for use in stretching hides, in various aspects the invention is not so limited and the repeated use of the term "hides" is for convenience and is to be taken as indicating generically any work which can be handled by apparatus embodying the invention.

Having thus described my invention, what I claim as new and desire to secure by Letters Patent of the United States is:

1. An apparatus for stretching hides having, in combination, a frame, a series of fixed flanges projecting from the frame to support a hide, and hide engaging members extending laterally from said flanges.

2. An apparatus for stretching hides having, in combination, a frame, a series of fixed projecting members distributed over the frame, and hide engaging members arranged in staggered relation on the projecting members.

3. An apparatus for stretching hides having, in combination, a series of supporting members, and hide engaging prongs secured to the supporting members below the upper edges of the latter.

4. An apparatus for stretching hides having, in combination, a series of projecting members, hide engaging prongs arranged in staggered relation on the projecting members, each projecting member being provided with cutaway portions opposite the hide engaging prongs on the adjacent projecting member.

5. An apparatus for stretching hides having, in combination, a series of projecting members, hide engaging prongs secured to

the projecting members below the upper edges of the latter, each projecting member having cutaway portions opposite the prongs on the adjacent projecting member.

6. An apparatus for stretching hides having, in combination, a frame, a series of projecting members extending from the frame and provided with openings, and hide engaging members passed through the openings of adjacent projecting members to secure said adjacent projecting members together. 70

7. An apparatus for stretching hides having, in combination, a frame having a series of hide supporting members, and hide engaging members secured to the supporting members in an inclined position below the upper edges of the latter. 80

8. An apparatus for stretching hides having, in combination, a series of projecting flanges, each having a series of upper and a series of lower openings, the upper openings of one flange being arranged opposite the lower openings of the next flange, and hide engaging members secured in the opposite openings. 85

9. An apparatus for stretching hides having, in combination, a frame, projecting flanges secured to the frame and each having a series of upper and a series of lower openings, the upper openings on one flange arranged opposite the lower openings of the next flange, and hide engaging members mounted in the opposite openings of adjacent flanges and arranged in staggered relation. 95

10. An apparatus for stretching hides having, in combination, a frame, supporting members on the frame, and hide engaging members secured to the supporting members for engagement with a hide, said hide engaging members being formed with diverging prongs at one end and with a split portion at the other end to secure them to the supporting members. 105

11. An apparatus for stretching hides having, in combination, a series of longitudinal and transverse hide supporting members, and hide engaging prongs secured to the supporting members below the upper edges of the latter. 110

12. An apparatus for stretching hides having, in combination, a frame, hide supporting members secured to the frame and arranged at an angle to each other, and hide engaging prongs secured to the supporting members. 120

13. An apparatus for stretching hides having, in combination, a frame, longitudinal and transverse supporting members secured to the frame, and hide engaging members secured to the supporting members and having diverging prongs. 125

14. An apparatus for stretching hides having, in combination, a frame, longitudi- 130

- nal and transverse members secured to the frame and meeting along a diagonal line, and hide engaging prongs secured to the members.
- 5 15. An apparatus for stretching hides having, in combination, a frame, longitudinal and transverse members secured to the frame and meeting along a diagonal line, and hide engaging members with diverging 10 prongs secured to the longitudinal and transverse members.
16. In an apparatus for stretching hides, hide engaging members having the forward portion of their bodies divided to provide 15 forwardly and laterally diverging prongs to penetrate the hide and hold it under tension in two directions, and means for rigidly supporting said members.
17. An apparatus for stretching hides 20 having, in combination, a frame, and a series of hide engaging members distributed over the frame with their shanks arranged parallel, said shanks each having one end formed into laterally diverging prongs to 25 penetrate the material and hold it under tension in a plurality of directions.
18. An apparatus for stretching hides having, in combination, a frame, and series of hide engaging members having shanks mounted at an angle to each other on the 30 frame, each shank having one end divided into diverging prongs to penetrate the material and hold it under tension in different directions.
19. An apparatus for stretching hides 35 having, in combination, a frame, and a plurality of series of hide engaging prongs occupying the greater part of the frame, some of said prongs being arranged at an 40 angle to the others.
20. An apparatus for stretching hides having, in combination, a frame, a plurality of hide engaging members having their shanks angularly arranged on the frame, some of the members being provided with 45 a plurality of forwardly diverging prongs, and means for supporting said members to resist strain in the line of their shanks.

In testimony whereof I have signed my name to this specification.

GEORGE GODDU.
